UNITED STATES PATENT OFFICE

HAROLD MORRISON, OF CHATTANOOGA, TENNESSEE, ASSIGNOR TO MILNE CHAIR COMPANY, OF CHATTANOOGA, TENNESSEE, A CORPORATION OF TENNESSEE

DESIGN FOR A CHAIR

Application filed May 4, 1933. Serial No. 48,010. Term of patent 3½ years.

To all whom it may concern:

Be it known that I, HAROLD MORRISON, a citizen of the United States, residing at Chattanooga, county of Hamilton, State of Tennessee, and whose post office address is c/o Milne Chair Company, in said city, have invented a new, original, and ornamental Design for a Chair of which the following is a specification, reference being had to the accompanying drawing, constituting a part thereof.

In the drawing:—

The figure is a front perspective view of the chair showing my new design.

I claim:

The ornamental design for a chair, substantially as shown.

In testimony whereof I have hereunto subscribed my name this 2nd day of May, 1933.

HAROLD MORRISON.
